United States Patent Office.

WILLIAM VOGEL, OF NORWICH, CONNECTICUT.

Letters Patent No. 91,692, dated June 22, 1869.

ASH-SIFTER.

The Schedule referred to in these Letters Patent and making part of the same.

To all whom it may concern:

Be it known that I, WILLIAM VOGEL, of Norwich, in the county of New London, and State of Connecticut, have invented certain new and useful Improvements in Ash-Sifters; and I do hereby declare that the following is a full, clear, and exact description thereof, reference being had to the accompanying drawings, and to the letters of reference marked thereon, which form a part of this specification, and in which—

Figure 1 represents a longitudinal section of my ash-sifter.

My invention relates to improvements in ash-sifters; and to this end,

It consists in the employment of an ordinary box, which is provided, on its inner side, with a spring, working in combination with an eccentric attached to the end of a crank, for the purpose of giving a lateral motion to the sifter.

It further consists in hinging the sifter to the frame, and retaining the same in place, by means of a rod, while the operation of sifting is going on, and detaching the same when the coal or cinders are to be removed, in combination with such other devices, the object of which will be hereinafter fully set forth.

To enable others skilled in the art to which my invention appertains, to make and use the same, I will describe its construction and operation.

In the accompanying drawings—

A represents an ordinary box, made in the shape seen in the drawing, said box being made with a tin flange, *g'*, around its inner surface, about half way down the box, the object of which will be hereinafter more fully described.

B is the sifter, which is hinged to the frame C.

The inner side of this frame is made with a channel, in order that the tin frame C, which is attached to the sifter, may fit tight against the wooden frame C.

One end of the sifter is provided with a rod, D; and when the sifter is ready for use, this rod passes over a pin or screw, E, attached to the inner surface of the wooden frame.

F is a spring, secured to the outer surface of the wooden frame C, the spring being made and secured as seen in the drawing.

a a are brackets attached to the side of the frame C, in order that the said frame may fit tight in the box A.

G is the eccentric, which consists of an ordinary wheel, with projections on the same.

This eccentric is attached to the end of the crank b, inside the box A, between the side of the box and the bar d, which holds one end of the crank.

I is a spring secured to the inner end of the box A, and so constructed that one end rests against the frame C of the sifter.

The front end of the box A is provided with a pivoted door, J, so that when the operation of sifting has finished, this door is opened, and the rod D is detached from the pin E, and the sifter is placed in a line with the door J, which allows the coal to pass out of the sifter into the receptacle for the same, which is placed under the door J.

K is a drawer placed under the sifter, for the purpose of receiving the ashes, the tin flanges *g'* being used to prevent the ashes from passing between the drawer and the sides of the box A.

My machine is thus operated:

The sifter is placed in the box A, resting on the brackets *d d*, the spring F coming in contact with the eccentric, G. Then, by turning the crank b, the projections on the eccentric strike the spring F, thus giving a lateral motion to the sifter, the spring I forcing the sifter back.

Having thus fully described my invention,

What I claim, and desire to secure by Letters Patent, is—

1. The rod D, when arranged and operated in the manner and for the purpose set forth.

2. In addition to the above, the eccentric, G, springs F and I, in combination with the sifter B and rod D, arranged and operated substantially in the manner and for the purpose set forth.

In testimony that I claim the foregoing as my own, I affix my signature in presence of two witnesses.

WILLIAM VOGEL.
